UNITED STATES PATENT OFFICE.

ADNA F. BLANCHARD, OF ATLANTA, GEORGIA.

VAPOR-LAMP.

1,117,769.

Specification of Letters Patent. Patented Nov. 17, 1914.

Application filed September 29, 1913, Serial No. 792,400. Renewed September 19, 1914. Serial No. 362,595.

To all whom it may concern:

Be it known that I, ADNA F. BLANCHARD, a citizen of the United States, residing at Atlanta, in the county of Fulton and State of Georgia, have invented new and useful 5 Improvements in Vapor-Lamps, of which the following is a specification.

The invention relates generally to an improvement in vapor lamps, and particularly 10 to a lamp of this type designed for the utilization of kerosene as a fuel and for the feeding of such fuel to the vaporizer by pressure caused by the heating of a confined body of air by the heat rising from the burner.

One of the objects of the present invention 15 is the provision of a pressure tank adapted to contain air under normal pressure and having direct communication with the fuel tank, the detailed structure of the 20 lamp parts compelling the travel of all air admitted to the lamp through the heated zone thereof, and the specific structure of the pressure tank insuring a rapid heating of the air therein from such heated product, 25 whereby the air within the pressure tank is compelled to exert a feeding pressure upon the fuel.

A further object of the invention is the 30 provision of means for admitting air to the mixing chamber in a manner to insure a proper mixture by causing the fuel stream to take up just sufficient of the admitted air to produce a proper mixture, the excess air being drawn downwardly by the heat at the 35 point of ignition and directed upwardly to heat the pressure tank.

The invention in the preferred form of 40 details will be described in the following specification, reference being had particularly therein to the accompanying drawings, in which:

Figure 1 is a vertical central section 45 through the improved lamp, the globe being broken away, Fig. 2 is an enlarged plan view with the pressure tank and co-operating supports removed, Fig. 3 is a bottom plan 50 view of the fuel tank and parts connected thereto, Fig. 4 is a section on line 4—4 of Fig. 1, Fig. 5 is a section on line 5—5 of Fig. 4, Fig. 6 is a section on line 6—6 of Fig. 4.

In the accompanying drawings I have 55 shown the preferred form of the details of structure of the improved lamp, and for the purposes of the following description such lamp may be said to comprise a main sec-

tion 1, including a fuel tank 2, which is in the form of an annular hollow body and is provided with the usual filling opening 3 having a sealing cap 4.

Arranged within the interior opening of 60 the fuel tank and connected thereto by plates 5 is a supporting section including outer and inner spaced walls 6 and 7, the latter being of materially less height than the former and the space between the plates being closed at the lower end by a bottom plate 8 circumferentially offset to form a shoulder 9 therein. To the upper edge of the outer plate is connected a cover plate 10, formed with a central opening 11, the cover plate sloping downwardly and inwardly from its outer edge to the edge of the opening 11. A bridge plate 12 is secured to the upper edge of the inner wall 7 of the 70 supporting section, being projected from such connection inwardly, downwardly and inwardly, and then upwardly, and connected to the edge of the opening 11 of the cover plate, the said bridge plate having a central 75 opening registering with the said opening of the cover plate. The outer wall 6 of the supporting section is formed on a line below the upper edge of the inner wall with an 80 annular row of openings 13, and the inner 85 wall 7 is formed with a similar row of openings 14, a portion of such wall however being free of such perforations. The outer wall 6 is cut out for a portion of its length to form an opening 15 and a door 16 is 90 slidably connected to said wall, and operated by a handle 17 whereby to close said opening when desired. A shield 18 is secured to the outer wall 6 throughout that 95 portion of the length of said wall beyond the opening 15, said shield having its ends connected to the wall, and being of such form and length as to overlie the openings 13. The shield is spaced from the wall at its lower edge and freely open, permitting 100 the air to pass beneath the shield and upwardly to reach the openings 13.

Within the fuel tank 2 is arranged a feed pipe 19 having the receiving end 20 protected by a strainer 21 and preferably arranged in a depending well 22 of the tank, the latter being closed by a cap 23 to provide access to the receiving end of the feed pipe when necessary. The feed pipe leads to and through a valve body 24 secured to 110 the tank and from said body to a pipe 25, a needle valve 26 controlling the passage of

fluid through the ports of the valve body in any usual or preferred manner. The needle valve is adapted for manual control from beyond the valve body in any conventional way, such for example as providing the stem of the valve with a cross bar 27, having depending flexible members by which the valve may be opened or closed.

A vaporizer 28 is arranged in the supporting section, within the inner wall 7. This vaporizer comprises a tube-like body into the upper portion of which at one end the feed pipe 25 leads, the vapor pipe 29 leading from the opposite end of the vaporizer, and being formed in a coil 30 beyond the vaporizer. The vapor pipe 29 beyond the coil leads to a jet nozzle 31 supported in the bridge plate 12, as shown in Fig. 5. The fuel pipe includes a main section 32 which extends through the coil 30 of the vapor pipe and depends below the supporting section, the lower end being formed in any appropriate way for the reception of the usual mantle. The upper end of the main section 32 is connected by a goose neck 33 with an entrance section 34, projecting through an opening in the cover plate and in line with the jet nozzle 31. The fuel pipe is supported by tie strips 35 secured there-to and to the upper surface of the cover plate.

By preference the supporting section is removably secured to the fuel tank by providing a clamping ring 36 designed to embrace the outer wall of the supporting section to which ring the plates 5 are secured, and also secured to this ring are diametrically opposed uprights 37 which project above the cover plate, their upper ends being longitudinally slotted at 38 and formed to provide eyes 39.

A pressure tank 40 is provided, through which one or more flues 41 are arranged, the flues being open at the ends and completely closed against the interior of the tank. In the form illustrated in Fig. 1, I have shown the tank as provided with a single flue, which opens at the top through the center and at the bottom to one side of the center. The flue or flues provide a passage for the heated air, whereby the temperature of the air within the tank is more quickly raised to the point necessary to induce the desired pressure. The tank is supported within an open pipe section 42, having a diameter greater than that of the tank and provided with bowed spring strips 43 between which the tank is held, the strips reinforcing the tank and supporting the same against independent movement under any usual jar of the lamp. The lower end of the pipe section 42 rests upon an outer annular shoulder 44 of the cover plate 10, and the pipe section 42 is completely inclosed in an ornamental cover section 45

supported upon an offset edge 46 of the cover plate. The cover section 45 projects above the pipe section and tank, and receives and supports a cover 47 having an edge flange 48 overhanging openings 49 formed in the cover section 45. The cover section 45 is provided with diametrically opposed projections 50 adapted to seat in the slots 38 at the upper ends of the arms 37, a pin being passed through the eyes 39 of the arms to removably secure the parts against separation. The cover 47 may be provided with any desired form of hanger 51 whereby the lamp may be hung.

A reflector 52 is hingedly connected to the outer edge of one of the plates 5, the opposing plate being provided with a catch 46' to engage a notch in the reflector plate to secure said plate in operative position when desired. The reflector is centrally formed with an opening 53 having an upturned edge flange 54, and within this flange which may if desired be integral is secured a cup for the initial heating of the vaporizer and tank. The cup comprises approximately a horizontal portion 55 formed with a series of openings 56, the inner edge of which is provided with an upstanding flaring flange 57. Secured to the inner edge of the horizontal portion 55 is a depending section 58 terminating in a semi-cylindrical annular member 59, forming the cup proper, and being if desired provided with a desirable quantity of wicking or absorbent material 60. The fuel pipe extends within the central space of the cup proper and projects below the same, and the depending portion 58, immediately above the cup proper is formed with openings 61, the horizontal portion 56 of the cup section being formed with similar openings 62. The bridge plate 12 of the supporting section, adjacent the opening 15 in the outer wall 6 of said section is provided with a tube 63 the lower end of which is immediately above the cup proper, so that alcohol, or similar fuel fed through said tube may be delivered to the cup. A cover plate 64 is hinged to the upper end of the tube 63 and connected to the door 16, the construction opening the tube while opening the door and closing the tube as the door is closed.

In the use of the lamp, the valve 26 is closed and alcohol, in sufficient quantity delivered to the cup 60, and ignited through the tube 63. The heat rising from the flame will raise the temperature of the air in the pressure tank, and by such expansion create a pressure upon the fuel in the tank 2, the air reaching the tank through a pipe 65 in open communication with both tanks. The valve 26 is then opened and fuel fed to the vaporizer, from which in form of vapor it passes to the jet 31. At this point it is mixed with air admitted through the openings 13 and over the upper edge of the

guard plate, and the mixture directed through the fuel pipe to the mantle.

With the reflector in operative position it will be noted that the upstanding flange 57 of the cup section forms an inner guard for the openings 14 in the inner wall of the supporting section, and hence the air to support combustion is drawn through the openings 13 and 14 and must pass upwardly over the flange 57 to reach the point of ignition. As the incoming air however is materially cooler than the air within the space included by the flange 57, the passage of the incoming air will be through the openings 62, so that the heated air, rising from the burner will find its way upwardly within the flange 57 through the opening 11 and around the pressure tank as well as through the flue or flues 41. Furthermore the fuel stream rising through the jet will take up just sufficient air for a proper mixture as the excess will find its way through the openings 14 in the inner wall 7 of the supporting section and to the point of ignition.

25 The improved lamp is by reason of the control of the air inlets particularly adapted for use in the open air as it will remain unaffected even in strong winds, and furthermore the respective walls and flanges of 30 the supporting section are so arranged as to protect the air current against the elements, thus insuring a steady even flame under ordinarily adverse conditions. The heated air rises practically directly to the pressure tank 35 and hence insures a uniformly high temperature of the air in said tank and a consequently steady and sufficient pressure upon the fuel in the tank. By reason of the indirect admission of the air to the mixing 40 chamber, the same will be heated to a considerable extent prior to the mixing of the vapor, hence insuring a more effective mixture, particularly with kerosene.

45 The improved lamp is shown as a hanging lamp, though it is to be understood that it may be varied in detail to provide any desired type of lamp, and that the various parts of the construction may be of any appropriate material or in any desired size.

50 Having thus described the invention what is claimed as new, is:—

1. A vapor lamp including an annular fuel tank, a supporting section arranged in the central space of the tank, said section comprising inner and outer spaced walls, each formed with openings, a cover plate secured to the upper edge of the outer wall and having a central opening, a bridged plate secured to the upper edge of the inner wall 55 and having a central opening coinciding with the opening of the cover plate, and a guard plate carried by the inner wall and terminating at its upper edge below the cover plate.

65 2. A vapor lamp including an annular

fuel tank, a supporting section arranged in the central space of the tank, said section comprising inner and outer spaced walls, each formed with openings, a cover plate secured to the upper edge of the outer wall 70 and having a central opening, a bridged plate secured to the upper edge of the inner wall and having a central opening coinciding with the opening of the cover plate, a guard plate carried by the inner wall and 75 terminating at its upper edge below the cover plate, a vaporizer carried by the supporting section and in communication with the fuel tank, a vapor pipe leading from the vaporizer and opening through the 80 bridge plate, and a fuel pipe opening through the cover plate with its receiving end in line with the terminal of the vapor pipe.

3. A vapor lamp including an annular fuel tank, a supporting section arranged in the central space of the tank, a vaporizer arranged in the supporting section and having valved communication with the tank, a vapor pipe leading from the vaporizer and 85 terminating in a jet within the supporting section, a fuel pipe carried by the supporting section and having its receiving end in line with and spaced from the jet, a reflector having hinged connection with the tank, a 90 starting cup carried by the reflector, and a feed pipe for the starting cup carried by the supporting section.

4. A vapor lamp including an annular fuel tank, a supporting section arranged in 100 the central space of the tank and including inner and outer spaced walls each formed with openings, a cover plate and a bridge plate forming with said walls an air chamber, means for admitting the vapor to said 105 air chamber, a guard plate partly closing the air chamber against air admission through the openings in the outer wall of the supporting section, a starting cup structure movably connected to the fuel tank, and a 110 flange carried by said structure to overlie the openings in the inner wall of the supporting section.

5. A vapor lamp including an annular fuel tank, a supporting section arranged in 115 the central space of the tank and including inner and outer spaced walls each formed with openings, a cover plate and a bridge plate forming with said walls an air chamber, means for admitting the vapor to said 120 air chamber, a guard plate partly closing the air chamber against air admission through the openings in the outer wall of the supporting section, a starting cup structure movably connected to the fuel tank, said 125 outer wall of the supporting section being formed with a door closed opening, a feed pipe carried by the supporting section for the starting cup, and a cover for said feed pipe 130 operated in the movement of the door.

6. A vapor lamp including an annular fuel tank, a supporting section arranged in the central space of the tank and including inner and outer spaced walls each formed with openings, a cover plate and a bridge plate forming with said walls an air chamber, means for admitting the vapor to said air chamber, a guard plate partly closing the air chamber against air admission through the openings in the outer wall of the supporting section, a starting cup structure movably connected to the fuel tank,

and a flange carried by said structure to overlie the openings in the inner wall of the supporting section, said structure being formed with openings outwardly beyond the flange to direct the incoming air below the starting cup. 15

In testimony whereof I affix my signature in presence of two witnesses.

ADNA F. BLANCHARD.
